FIG-6

FIG. 7

FIG. 1 is a front elevational view of a typewriter showing my new design;

FIG. 2 is a rear elevational view thereof;

FIG. 3 is a top plan view;

FIG. 4 is a right side elevational view;

FIG. 5 is a left side elevational view;

FIG. 6 is a front perspective view; and

FIG. 7 is a rear perspective view thereof.

The essential features of the design reside in the portions shown in solid lines on the drawing.

I claim:

The ornamental design for a typewriter, substantially as shown and described.
